S. A. BOYLEN.

MYSTERY CLOCK.

APPLICATION FILED OCT. 16, 1915.

1,185,624.

Patented June 6, 1916.

UNITED STATES PATENT OFFICE.

STEPHEN ARTHUR BOYLEN, OF MYSTIC, CONNECTICUT.

MYSTERY-CLOCK.

1,185,624.

Specification of Letters Patent. Patented June 6, 1916.

Application filed October 16, 1915. Serial No. 56,198.

To all whom it may concern:

Be it known that I, STEPHEN ARTHUR BOYLEN, a citizen of the United States, and resident of Mystic, in the county of New London and State of Connecticut, have invented certain new and useful Improvements in Mystery-Clocks, of which the following is a specification.

My invention relates to clocks and particularly to so called mystery clocks.

The object of my invention is to provide a mystery clock presenting attractive and interesting illusory effects.

The invention consists of a mystery clock embodying the peculiar features of construction and mode of operation set forth in the following description and particularly pointed out and defined in the claims at the close thereof.

20 In the accompanying drawings: Figure 1 is a front elevation, partly broken away, of my new mystery clock. Fig. 2 is a side elevation of the clock shown in Fig. 1. Fig. 3 is a rear elevation of the upper portion or head of the clock shown in Figs. 1 and 2. Fig. 4 is a section on line 4—4 of Fig. 1. Fig. 5 is a section on line 5—5 of Fig. 1. Fig. 6 is a sectional detail on line 6—6 of Fig. 4.

30 The embodiment of my invention herein shown provides a small, compact clock that is especially adapted for use upon a desk, mantel or the like, or as a window attraction, and as shown in the drawings it comprises a base 1 formed with an interior chamber 2 within which is arranged a movement 3 of ordinary construction which is fastened in place within said chamber by screws 4. The screws 4 also secure a metal socket 5 to the top side of base 1, the lower end of a hollow transparent post 6 being firmly secured within said socket by means of cement 7. The post 6 is preferably a piece of glass tubing and the upper end thereof is secured within a metal socket 9 by means of cement 8. This socket 9 is integral with an upright ring-shaped head 10 that is made with an inwardly extending flange 11 bearing upon its outer side dial markings to indicate hours, half-hours and quarter-hours, as shown in Fig. 1.

35 To the inner side of flange 11 a transparent pane 12 of glass or other suitable material is secured by cement 13, and at its middle this pane is formed with a perfora-

tion within which is cemented, or otherwise secured, a bushing 14 rotatably supporting a spindle 15. At its front end the spindle 15 carries a hand 16 coöperating with the dial markings upon the exterior of flange 60 11, while the rear end of said spindle carries a transparent pane 16 of glass or other suitable material formed at its middle with a perforation to receive the end of said spindle which is cemented therein, or otherwise 65 fastened so that this pane and the spindle must rotate together.

Surrounding the pane 16 and cemented to its periphery is a gear ring 17 which may be made from hard rubber, or other suitable material, said gear ring meshing with a pinion 18 carried by a spindle 19. The spindle 19 is journaled in the top wall 20 of socket 9 and extends below said wall into post 6 where its lower portion is secured 75 within the upper end of a transparent shaft 21, of glass or other suitable material, by means of a body of cement 22. The transparent shaft 21 extends downwardly 80 through the hollow transparent post 6 and within its lower end the minute hand shaft 23 of movement 3 is secured by a body of cement 24.

In order that access may be had to the movement 3 when the instrument requires 85 to be wound or set, the chamber 2 is made to extend out to one side of base 1 and this part of said chamber is closed by a door 25 secured to base 1 by two screws 26 and 27. By removing screw 26 the door 25 may 90 be swung aside on screw 27, as indicated by dotted lines in Fig. 1, to permit of the insertion of the winding and setting instruments (not shown) which will be provided with each clock. Into the rear end of ring 10 is forced another ring 28 which covers and hides the gear ring 17 from the rear, the flange 11 hiding said gear ring from the front. In order to hide the pinion 18 the back ring 28 is made with an integral 100 cover 29 fitting over said pinion.

As herein shown the dial of the clock is marked with the hours 1 to 12 and since the pinion 18 is connected with and driven by the minute hand shaft of movement 3 so that it makes one revolution every hour, the ratio of the gearing 17 and 18 is made one to 12 which causes the hand 16 to traverse the dial once in every twelve hours.

105 To the eye of the observer the transparent 110

driving shaft 21 cannot be detected or distinguished through the transparent post 6 and since the head of the clock is not shaped, or of sufficient size, to contain the movement, the illusion is presented of a hand traversing a dial without being connected with an actuator. This illusion is enhanced by the seeming fact that the hand carrying spindle 15 has no power transmitting means connected with it, the annular head 10 being separated from it by the surrounding stationary pane 12 and the apparently stationary transparent pane 16, through both of which distant objects may be observed.

15 As a matter of fact the two panes 12 and 16 appear to the eye as a single pane when viewed from the front or rear, the movement of pane 16 being so slow—one revolution every twelve hours—that it seems stationary and appears to be the rear side of pane 12. Therefore, the hand 16 appears to be supported by a single stationary pane at the middle of which it is mounted upon an isolated spindle so as to traverse the dial 25 of itself, apparently, and without apparent connection with an actuating means.

What I claim is:

1. A mystery clock comprising a base; a hollow transparent post fixed at its lower end to said base; a head fixed to the upper end of said post; a pane of transparent material rotatably supported within said head and provided with an index; a movement mounted within said base, and transparent means extending up through said hollow post and invisible from the exterior of the latter through which said movement rotates said pane of transparent material.
2. A mystery clock comprising a base; a hollow post of transparent material fixed at its lower end to said base; an annular head fixed to the upper end of said post; a pane of transparent material rotatably supported within said head and provided with an index; a movement mounted within said base; a shaft of transparent material within said hollow post connected at its lower end with said movement, and means near the upper end of said shaft through which the latter rotates the pane of transparent material.
3. A mystery clock comprising a base; a

movement mounted within said base; a hollow post of transparent material fixed at its lower end to said base; an annular head 55 fixed to the upper end of said post; a pane of transparent material fixed in position within said annular head; a spindle rotatably supported by said fixed pane; a hand carried by said spindle; a pane of 60 transparent material fixed to said spindle; a shaft of transparent material within the hollow post having its lower end connected with said movement, and means near the upper end of said shaft through which the 65 latter rotates the pane of transparent material that is on the spindle.

4. A mystery clock comprising a base; a hollow post fixed at its lower end to said base; an annular head fixed to the upper 70 end of said post; a pane of transparent material rotatably supported within said head and provided with an index and with gear teeth near its periphery, said gear teeth being hidden by said head; a movement mounted within said base; a pinion meshing with the teeth on the rotatable transparent pane, and a connection between the pinion and movement extending through said hollow post.

5. A mystery clock comprising a base; a hollow post fixed near its lower end to said base; an annular head fixed to the upper end of said post; a pane of transparent material fixed in position within said annular head; a spindle rotatably supported by said fixed pane; a hand carried by said spindle; a pane of transparent material fixed to said spindle and provided near its periphery with gear teeth, said teeth being 85 hidden by said head; a pinion meshing with the teeth on the rotatable pane; a shaft of transparent material to one end of which said pinion is connected, said shaft being arranged within the hollow post, and a 95 movement mounted within said base with which said shaft is connected.

In testimony whereof I have affixed my signature, in presence of two witnesses.

STEPHEN ARTHUR BOYLEN.
